UNITED STATES PATENT OFFICE

JOHN D. MOHR, OF NEWARK, NEW JERSEY

STAMP AFFIXING MACHINE

Application filed December 21, 1929. Serial No. 415,633.

This invention relates to stamp affixing machines especially adapted for use in connection with postage stamps.

It is an object of the invention to provide in a stamp affixing machine a mechanism by means of which postage stamps and the like may be accurately fed into a position so that they may be affixed to a surface.

A further object is the provision of a simple device for moistening the gummed side of a stamp automatically.

A further object is the provision of a stamp affixing machine, simple in structure and having a relatively small number of parts.

These and other advantageous objects, which will later appear, are accomplished by the simple and practical construction and arrangement of parts hereinafter described and exhibited in the accompanying drawings, forming part hereof, and in which:

Figure 1 represents an elevational view in section of a stamp affixing machine.

Figure 2 represents a sectional view taken on the line 2—2 of Figure 1.

Figure 3 represents a sectional view taken on the line 3—3 of Figure 1.

Figure 4 represents a sectional view taken on the line 4—4 of Figure 1.

Figure 5 represents a side view of a portion of the stamp affixing mechanism.

Figure 6 represents a sectional view taken on line 6—6 of Figure 5.

Referring to the drawings, the device is shown to include an intermediate casing 7 in the upper portion of which is inserted a lock collar 8 through which slidably passes an operating shaft 9.

Attached to the lower end of the shaft 9 is a plate 10 having an upturned portion 11 to which is attached a knife blade 12, and an upturned portion 13 having a right angular flange 14. A pad 15 preferably of rubber, is attached to the underside of the plate 10.

Attached to a loop 16 an integral part of the plate 10, is one end of the tension springs 17, having their other ends connected with a pin 18 mounted in the walls of the casing.

Shaft 9 has attached thereto a transverse pin 19 adapted to engage a notch 20 on a right angular lever 21 pivoted at 22 to the arm 23 of

The lower arm of the lever 21 is normally urged upwardly by tension springs 25 connected thereto and to the prongs 53 of the bridge 38. Attached to the arms 23 is a plate 29 having integral fingers 26 movable in grooves 28 of a corrugated arcuate guide plate 31.

Loosely positioned in the grooves 28 and attached to ledge 27 of the casing 7 are a plurality of resilient wires 30, which normally tend to hold a strip of stamps 33 smoothly against guide plate 31, the flanges 32 at the sides of the plate preventing lateral movement of the stamp strip.

The stamps are provided in a roll 34 which is pivotally mounted upon the shaft 35 supported by brackets 36 attached to the walls of the casing 7.

At the lower end of arcuate guide plate 31 is mounted a knife blade 37 which opposes the blade 12 to shear stamps from the strip 33 at the proper time.

The springs 17 normally hold the shaft 9 in a raised position as shown in Figure 1, and cause flange 14 to engage the bridge 38 on plunger 39 to move the latter upwardly against the resistance of the compression spring 40 and tension springs 25. The lower end of the plunger 39 has a reduced portion 41 slidably mounted in a cylinder 42 which has an aperture in which is inserted a small tube 43, leading to the opening 50 and which is closed by the chamois piston 44 attached to plunger 39 when the latter is in a raised position.

The plunger 39 has a further reduced portion 45 between the portion 41 and the piston 44. The lower end of the cylinder 42 contains a ball 46 adapted to close the aperture 47 in the bottom of the cylinder against the flow of water back to chamber 48 when piston 44 is descending and portion 41 is discharging water through tube 43 to opening 50.

In operation, the plunger 9 is depressed to cause pin 19 to engage the notch 20 in lever 21 to swing the arms 23 downwardly so that the

fingers 26 on the plate 29 may engage in the perforations 49 which divide the stamps.

By this means the stamps are accurately fed downward since there will be no feeding movement until the fingers 26 have engaged a row of perforations 49. When the arm 23 is moved down a predetermined distance, that is the distance between perforations in the stamp strip, into a position as shown in Figure 5, directly beneath the rubber pad 15, the pin 19 becomes disengaged from the notch 20 on account of the angular change of the position of the pivot pin 22, and springs 25 return the yoke arms 23 and levers 21 to their initial position.

As the plunger moves downwardly the compression spring 40, in conjunction with springs 25 the ends of which are secured to the levers 21 and to the prongs 53 on bridge 38, force the plunger 39 downwardly to a position whereby the chamois piston 44 will not cover the opening to tube 43 in the cylinder 42, and water surrounding the reduced portion 45 of the plunger 41 is forced through tube 43 on to the surface to which the stamp is to be affixed.

At the same time the plunger 9 continues downwardly and the knife blades 12 and 37 shear the stamp off at the point 52 along the line of perforations 49, and the pad 15 presses the stamp firmly upon the moistened surface.

The plunger 9 is returned automatically to its raised position by tension springs 17, which carry upwardly with them the plunger 39, closing the opening to tube 43 in cylinder 42 to prevent water leaking from tube 43 at opening 50; and to retain an amount of water at reduced portion 45 to act as a cushion to force water out of opening in cylinder 42 through tube 43 to opening 50 when water is forced by piston 44 from chamber 51 on the downward stroke of plunger 39. In order to prevent buckling of the strip of stamps from the lower ends of wires 30 to point 52, the guide 31 has its lower portion covered by a plate 54.

The foregoing disclosure is to be regarded as descriptive and illustrative only, and not as restrictive or limitative of the invention, of which obviously an embodiment may be constructed including many modifications without departing from the general scope herein indicated and denoted in the appended claims.

Having thus described my invention, what I claim as new and desire to secure by Letters Patent, is:

1. In a machine of the class described, a corrugated guide, a pivoted yoke, having a plurality of fingers projecting into the corrugations of the guide, a plunger, and means associated with the plunger and yoke to rotate the latter when the plunger is depressed.

2. In a machine of the class described, a

corrugated guide, a plurality of resilient wires bearing against the guide, a pivoted yoke, a plate having a plurality of fingers projecting into the corrugations of the guide between the wires, said plate being attached to the yoke, a plunger, and means associated with the plunger and yoke to rotate the latter when the plunger is depressed.

3. In a machine of the class described, a corrugated guide, a plurality of resilient wires bearing against the guide, a pivoted yoke having projections adjacent the guide, and means to swing the yoke.

4. In a machine of the class described, a plunger, resilient means for holding the plunger in a raised position, a transverse pin mounted on the plunger, a pivoted yoke, a lever pivoted on said yoke and having a notch adapted to be engaged by the pin when the plunger is depressed, and resilient means for retaining said lever in a predetermined position when the plunger is in a raised position.

5. In a machine of the class described, a plunger, means for normally holding the plunger in a raised position, a pivoted yoke, a lever pivoted on the yoke, means on the plunger engaging the lever during a predetermined downward movement of the plunger, and means for retaining the lever in a predetermined position when the plunger is in a raised position.

6. In a machine of the class described, a plunger, means for normally holding the plunger in a raised position, a pivoted yoke, a lever pivoted on the yoke, means on the plunger engaging the lever during a predetermined downward movement of the plunger, means for retaining the lever in a predetermined position when the plunger is in a raised position, a surface moistening device, and means connecting the moistening device with the plunger to operate in timed relation therewith.

This specification signed this 18th day of December, 1929.

JOHN D. MOHR.
